(57) **CLAIM**

The ornamental design for a medication dispensing device holder as shown.

DESCRIPTION

FIG. 1 is a front, top, right perspective view showing my new design;

FIG. 2 is rear, top, right perspective view thereof;

FIG. 3 is a front, top, left perspective view thereof;

FIG. 4 is a rear, top, left perspective view thereof;

FIG. 5 is a front view thereof;

FIG. 6 is a rear view thereof;

FIG. 7 is a left-side view thereof;

FIG. 8 is a right-side view thereof; and,

FIG. 9 is a top plan view thereof.

The broken lines depict portions of the article that form no part of the claimed design.

1 Claim, 9 Drawing Sheets(56)
